I. BRANDT

JEWELRY DISPLAY CASE

Filed June 11, 1923

Inventor:

Ivorine Brandt.

UNITED STATES PATENT OFFICE.

IRVING BRANDT, OF CHICAGO, ILLINOIS.

DESIGN FOR A JEWELRY-DISPLAY CASE.

Application filed June 11, 1923. Serial No. 6,456. Term of patent 3½ years.

To all whom it may concern:

Be it known that I, IRVING BRANDT, a citizen of the United States, residing at Chicago, county of Cook, State of Illinois, have invented a new, original, and ornamental Design for Jewelry-Display Case, of which the following is a specification, reference being had to the accompanying drawing, forming part of this specification.

Figure 1 is a front elevation in perspective of a jewelry display case showing my new design and Fig. 2, is an end view of the same on a reduced scale.

What I claim and desire to secure by Letters Patent of the United States is:

The ornamental design for a jewelry display case, as shown.

IRVING BRANDT.
